ATTORNEY

UNITED STATES PATENT OFFICE.

ALEXANDER GORDON, OF CINCINNATI, OHIO.

RAILROAD-CAR-AXLE LATHE.

SPECIFICATION forming part of Letters Patent No. 252,030, dated January 10, 1882.
Application filed July 18, 1881. (No model.)

To all whom it may concern:

Be it known that I, ALEXANDER GORDON, a subject of Great Britain, and a resident of Cincinnati, Hamilton county, Ohio, have invented certain new and useful Improvements 5 in Car-Axle Lathes, of which the following is a specification.

This invention relates to car-axle lathes arranged to carry the axle upon two dead-centers, the driving mechanism operating at some 10 middle point of the axle's length, while each end of the axle may be turned without shifting the driving-dog, and to lathes generally in which the so-called "universal" or "Clement" 15 driver is used, said Clement driver consisting of a dog-pin plate fitted against the face-plate of the lathe and arranged to move upon said plate diametrically, and having two driving-pins projecting from it in a plane at right angles 20 to the line of said diametrical motion, whereby the axle being turned may occupy in its revolutions various positions slightly eccentric to the axis of the driving device.

The object of this invention is to prevent the 25 sagging and trembling of the axle, which generally result from the weight of the driving-plate, which at two points in the revolution of the axle is suspended by the axle.

In double lathes the driver is generally fixed 30 at about the center of the length of the axle, so as to equalize the torsion in turning the ends. The deflection caused by the weight of the driver is often as serious a matter as the unequal torsion guarded against. By my arrangement 35 I locate the driver as close to one end of the axle as the carriage and tool manipulation at that end will permit; and, furthermore, the driving-plate has a yielding support independent of the axle, thus preventing its periodical 40 dropping and jarring.

In the accompanying drawings, Figure 1 is a side elevation of a double-axle lathe embodying my improvements. Fig. 2 is a side elevation of the driving-head, and Fig. 3 a front 45 elevation of the driving-head.

In the drawings no attempt has been made to detail parts not considered pertinent to my improvements.

A is the bed of the lathe; B, one center stock, 50 and C the other center stock, the latter having its usual adjustable spindle.

D D are the two carriages, one for operating on each end of the axle.

E is the bearing of the driving mechanism, constructed substantially as usual, except that 55 it is gibbed, as at J, or otherwise fitted to slide upon the bed. Both the center stocks, B and C, are adjustable upon the bed.

The driving apparatus is clearly shown in 60 Figs. 2 and 3.

E is the main bearing; F, the main gear, journaled in said bearing, and having open center S; L, the usual pinion-shaft, which may be located inside the bed or at the back of the bed, or in any of the usual positions; M, the 65 driving-pinion gearing into the main gear F.

N is a bearing attached to the main bearing E. The pinion M is journaled into this bearing N, so as to partake of all the movements of the main bearing. The driving-shaft L is 70 splined, to permit the pinion to slide and be driven at any point.

J are the gibbs which attach the driving mechanism to the lathe-bed.

G is the usual driving-plate, having the usual 75 dog-studs, H, and attached in the usual manner to the main gear F by the bolts I, working in slots. When the driving-plate G is in the position shown in Fig. 3 its obvious tendency is to fall vertically, as far as the bolts I will permit. This tendency to drop occurs at each half-revolution of the lathe. This tendency is often 80 corrected in a degree by bolting the driver so tightly to the main gear that the friction will support it, spring-washers being placed under 85 the heads of the bolts I to produce a yielding friction-pressure; but this plan detracts considerably from the essential sensitiveness of the driving-plate.

In order that the weight of the driving-plate 90 may not cause undue deflection of the axle, I drive the axle from a point as close to one end as a double lathe will permit. In order to do this I adjust the two center stocks, B and C, so as to bring the driver at the proper point 95 on the axle; or I adjust the driving mechanism into proper relation to the two center stocks, all these parts being adjustable upon the lathe-bed, as mentioned.

In order to still further suppress the tendency of the driver-plate G to cause deflection 100 of the axle, I support it on a yielding bearing,

K, which is in turn supported by the spring Q, resting on the bridge O, which is attached to the driving-head by the studs P. The spring Q should be supple and of such stiffness as to nicely hold the driving-plate in central position. The bearing K has a stud or stem, R, fitting into the bridge O, as shown, to steady it.

The bridge O, instead of being attached to the driving-head, may be arranged to rest upon the lathe-bed; or it may be supported in any other suitable manner.

If desired, two or more bearings may be used in the same manner as the single bearing, and a counterbalancing-weight may obviously be substituted for the spring without departing from the principle of this invention.

I claim as my invention—

1. In double axle-lathes, the combination of a lathe-bed, two center stocks, one or both of

which are adjustable upon the lathe-bed, two tool-carriages located between the said center stocks, and an open driving mechanism of the Clement type, as set forth, located between said tool-carriages, and provided with attaching-gibs for uniting it adjustably to the lathe-bed, substantially as and for the purpose set forth.

2. In lathe-drivers of the Clement or self-adjusting type specified, the combination of a circular self-adjusting driving-plate, and a yielding bearing located below said plate to prevent its periodical dropping, substantially as set forth.

ALEXANDER GORDON.
